Design for the Plates of a Cook's Stove

The schedule referred to in three letters, it is understood making part of the same.

Seal when it may concern

Be it known that we, G. Smith and H. Brown of Philadelphia, County of Philadelphia, State of Pennsylvania, have invented or produced a new and original design for the plates of the Dictator cook stove, and we do hereby declare the accompanying drawing with the following explanation of the same to form a full,
clear and exact description of the said design.

In the accompanying drawing

Fig. 1 a front plate of the Dictator Cook Stove.

Fig. 2 a side plate, and

Fig. 3 the back plate.

At each edge of the front plate, is a plain moulding
a. adjacent to which on the plate is an ornamental figure of the form shown in the drawing. Each of the legs is bedded with a plain iron plate, and in the centre of the door is an ornamental figure.

DFS. 2272

At the edges of the side plates are plain mouldings dashed, and the side plates are hung two doors, each of which is edged with a plain moulding.

In the centre of the doors are two ornamental figures, and 2 of the form shown in the drawing.

Below the doors stand two ornamental panels
in which are the words "Abbott & Fobles Philadelphia".

At the edges of the back plate are three panels, in each of which is an ornamental figure.

Witnesses

The design for the plates of the "Dictator" cook stove substantially as above is made by the accompanying drawing.

Witnesses - In testimony whereof we have signed our names to this specification in the presence of two subscribing witnesses.
